CLAIM

The ornamental design for a display and earpiece for a handset, as shown and described.

DESCRIPTION

FIG. 1 is a front, bottom, right side perspective view of a display and earpiece for a handset, showing our new design; FIG. 2 is a front elevational view thereof; and, FIG. 3 is a top, left side, front perspective view thereof. The broken lines showing an outline of the handset is for illustration purposes only and forms no part of the claimed invention.

1 Claim, 3 Drawing Sheets

FIG. 1

FIG.2
